UNITED STATES PATENT OFFICE.

ALBERT E. BRADLEY, OF BRIDGEPORT, CONNECTICUT.

CUE TIP.

Application filed August 29, 1924. Serial No. 734,995.

To all whom it may concern:

Be it known that I, ALBERT E. BRADLEY, a citizen of the United States of America, and a resident of Bridgeport, in the county 5 of Fairfield and State of Connecticut, have invented a new and Improved Cue Tip, of which the following is a description.

My invention relates to cue tips having means to detachably secure them to the cue 10 and more particularly the present invention is intended as an improvement on the cue tip forming the subject-matter of a United States Letters Patent granted April 17, 1923, Number 1,452,420.

15 The special object of the present invention is to provide an improved means for effecting the connection between the cue and the tip.

The nature of the invention and its advantages will clearly appear as the description proceeds.

Reference is to be had to the accompanying drawings forming a part of this specification, it being understood that the drawings 25 are merely illustrative of one example of the invention.

Figure 1 is a side elevation of a portion of a cue equipped with my improved tip;

Figure 2 is a partly sectional side elevation;

Figure 3 is a view of the inner end of the tip and its fastening member.

In the illustrated example, 10 represents the front portion of a cue having a tenon

11 thereon. Fitted on tenon 11 is a sleeve 35 12 which seats firmly against the end of the cue 10 and extends beyond the same, the front end of said sleeve forming a socket.

The tip includes the usual disk 13 of leather and applied to the back of said disk 40 13 is a metallic disk 14. Projecting rearwardly from the disk 14 centrally thereof is a stud 15.

The bore of the sleeve 12 is cylindrical 45 and the stud 15 on the tip is tapered to have a tapered fit in the front end of said bore. The tapered form of the stud 15 insures a tight fit of the stud and a secure holding of the tip in place on the cue at all times. The arrangement positively insures against looseness of the tip and marks 50 an improvement over a threaded connection between the tip and the sleeve 12.

Having thus described my invention, I claim:

A cue formed with a tenon at the front 55 end, a sleeve having a cylindrical bore, the inner end of the sleeve being seated on the cue at the base of said tenon and the front end of the cue extending beyond said tenon and forming a socket, and a cue tip comprising a leather disk, a metallic disk affixed to said leather disk at the back thereof and a tapered stud central on the metal disk at the back thereof and tightly fitting in 60 the front projecting end of the said sleeve. 65

ALBERT E. BRADLEY.
